C. P. TRIMBLE

CUSHION SEAT AND THE LIKE

Filed March 20, 1925

By K. P. Mc Elroy
His Attorney

UNITED STATES PATENT OFFICE.

CHARLES P. TRIMBLE, OF PITTSBURGH, PENNSYLVANIA, ASSIGNOR TO FORT PITT BEDDING COMPANY, OF PITTSBURGH, PENNSYLVANIA, A CORPORATION OF PENNSYLVANIA.

CUSHION SEAT AND THE LIKE.

Application filed March 20, 1925. Serial No. 17,057.

This invention relates to cushion seats and the like and it comprises a bottom border frame, advantageously of wire provided with transverse, preferably longitudinally 5 arched, channel bars or angle irons, each having a longitudinally reinforced boss along the entire top and sets of perforations through the side walls thereof, the channel bar at each end being flattened and the flattened ends bent downwardly at substantially right angles to the bars and securely wrapped (advantageously from the inside, out) around opposite sides of the bottom frame, together with coil springs attached 10 to the channel bars by insertion of the lowermost coil of each spring through a set of perforations in the bars and means for preventing movement of the channel bars upon the frame; all as more fully hereinafter set 15 forth and as claimed.

Among other objects of my invention is the provision of an extremely simple cushion seat of great rigidity and strength and the provision of a cushion, the parts of which 20 can be easily, cheaply and quickly assembled. The frame together with the spring supporting channel bars may be made of stamped or pressed metal and after assemblage there results a spring seat of rigid construction. 25 The channel bars are particularly designed to afford the greatest possible resistance to stresses and strains and are extremely simple in their construction. The bars provide space for a clamping tool to attach them and 30 when positioned, leave space so the fabric may be readily trimmed and clamped.

In constructing covered cushion seats, it is always difficult to apply the covering and the cover holding means to the bottom 35 frame. This is particularly true when it is desired to trim the inside edges of the covering material. In using a simple U-shaped 40 clamp for holding the covering around the bottom frame, it is necessary to provide the 45 channel bars with specially adapted means for permitting the adjustment of the clamp, with the result that the channel bar is weakened and thereby made less rigid and less capable of withstanding the shocks to 50 which in use it is subjected.

It is one of the objects of this invention to provide channel bars which are capable

of withstanding shocks and at the same time permit ready wrapping of the covering around the lower border frame and permit 55 the inside edges of the covering to be easily trimmed, while at the same time offering no obstructions to the application of the cover clamping means.

It is also an object of this invention to 60 eliminate the tendency of the spring supporting bars to slide back and forth upon the bottom border frame. In seats having spring supporting bars with flattened ends wrapped around a border wire, it is found 65 that unless some special means is provided for preventing it, the bars will be found to slide backward and forward upon the border frame, especially during shipment and use. By providing the frame with deformed portions adjacent the ends of the spring supporting bars, I am enabled to overcome this 70 sliding by a simple and inexpensive procedure.

In the accompanying drawing showing 75 one form of a specific embodiment of my invention and in the views of which similar reference numerals designate corresponding parts,

Fig. 1 is a segmental perspective view of 80 a portion of the cushion seat;

Fig. 2 is a section along line 2—2 of Fig. 1, showing the cover and cover clamping means in position around the border frame;

Fig. 3 is a detailed horizontal section 85 along line 3—3 of Fig. 1;

Fig. 4 is a detailed end view of Fig. 2 without the covering and covering clamping means;

Fig. 5 is a similar view showing a modified form of means for preventing longitudinal movement of the channel irons and 90

Fig. 6 is a horizontal section through Fig. 5.

Referring to the drawings, reference numeral 1 designates the lower border frame which may be of wire or the like. Mounted to engage opposite sides of the border frame 1 are a plurality of spring supporting bars 2 of approximately inverted U or V-shape each having a longitudinal reinforcing boss 3 along its top and preferably extending 100 slightly over the bent ends. The bars are preferably arched longitudinally. The ex-

tremities of the bars are flattened as at 4 and may be perforated as at 5. The flattened extremities of the bars which are substantially wider than the width of the bars are bent 5 downwardly at substantially right angles to the bar and are wrapped around the lower border wire 1 by means of a suitable tool. This wide end gives a large gripping surface. Since the plane of the bars is substantially above the plane of the border frame, sufficient room is provided for the 10 operation of the tool. When the flattened extremities 4 of the channel bar are wrapped around the bottom border frame 1, there may be formed on the latter, through 15 perforations 5, deformed or swaged portions 6. These may be made by means of a punch or the like upsetting the metal around the punch hole and resulting in a projection 20 which secures the channel bars against longitudinal movement on the border wire. Near the top of the channel bar at intervals along its length are sets of perforations arranged for reception of the lowermost coil 25 of coil springs 7. The extreme ends of these springs after passing through these perforations may be bent to prevent accidental dislocation. The springs are attached to the top of the seat in any appropriate manner.

The seat is provided with a cover 8 of leather or the like which is wrapped around the lower border frame and is securely clamped therearound by means of clamps 9. 35 The clamps for this purpose may be of any type, such as the clips shown and claimed in my copending application Serial No.

586,223. The channel bars, as described, are constructed in such a way that the plane of the lower edge of the channel bar is substantially above the plane of the lower border frame, due to the provision of the downwardly extending flattened portions adjacent the ends of the bars. This construction permits ready application of the covering material 8 around the bottom border frame and leaves space for ready trimming of the inside ends of the covering. This construction of the channel bars also permits the ready clamping of the cover holding clips 50 in place by means of a suitable tool which can be worked from one end of the seat to another without meeting any obstruction.

A slightly modified means which may be used to prevent the longitudinal movement 55 of the channel bar on the bottom wire is that shown in Figs. 5 and 6. As illustrated, the swaged portions 6, formed by a punch or the like are spaced apart a distance corresponding to the width of the flattened end of the channel bar and the upset portions so formed secure the bar in place.

What I claim is:—

In a cushion or seat having springs and a lower border frame, spring supporting 65 bars having flat ends, the ends of the bars being perforated and wrapped around the frame and the frame being provided with swaged portions engaging the metal around said perforations to prevent longitudinal 70 movement of the bars.

In testimony whereof, I have hereunto affixed my signature.

CHARLES P. TRIMBLE.
